KEEPER FOR TRAVELING BAG FRAMES

Allen T. Long, Petersburg, Va.

Application December 31, 1936, Serial No. 118,688

3 Claims. (Cl. 292—340)

This invention relates to the frames of bags, satchels and the like, and particularly to those frames in which slotted keepers, angular in cross-section, are attached to one frame of the bag and latches are pivoted to the complementary outer frame of the bag, the latches having tangs which, when the latches are turned down against the frame, extend through the slots of the keepers and hold the bag closed, such latches and keepers being commonly found on what are known as Gladstone bags or traveling bags of like character.

The object of my invention will be best seen after consideration of certain figures of the drawing.

My invention is illustrated in the accompanying drawing wherein:

Figure 1 is a longitudinal fragmentary section through a bag frame with my improved keeper applied thereto.

Figure 2 is a section on the line 2—2 of Figure 1.

Figure 3 is a like section to Figure 2 but showing the latch partially depressed against the inclined portion of the keeper.

Figure 4 is a perspective view of the keeper.

The object of the present invention is to so form the keeper that when the tang of the latch is depressed, within frames not fully in register, the tang will be guided into the slot of the keeper and the frames will be drawn together by the latching action.

As will be seen from Figures 1 to 4, B designates one of the sheet metal frames and C the opposed sheet metal frame. These are angular in cross-section and the horizontal flange c of the frame C overlaps the relatively short flange b of the frame B. Attached to the inner face of the frame B is the keeper 10 which consists of a strip of relatively rigid stamped metal preferably steel, this keeper 10 being angularly bent so as to provide an attaching flange 11 which is riveted or otherwise attached, as at 12, to the inner face of the frame B below the flange b thereof. The body of the keeper extends laterally outward from the flange 11 and is formed with a longitudinally extending slot 13, as usual. The particular improvement of the keeper consists in bending the outer margin 14 of the keeper upward and laterally at an angle of approximately 45° to the horizontal portion of the keeper, this inclined margin 14 extending to one margin of the slot 13 or, in other words, all that portion of the keeper outward of the slot 13 is bent upward at an inclination to the body of the keeper.

I have illustrated a common form of latch

which is no part of my invention, the latch having a body 15 riveted or otherwise attached to the frame C, this latch having a hinged hasp 16 formed with a tang 17 which extends downward in a curve toward the outer end of the bag. This tang is provided with a stop lug 18 at its extremity. A spring 19 normally holds the hasp either in a raised or lowered position. When the hasp is lowered, the tang, of course, extends through a slot in the flange c and through the slot 13. When the hasp 16 is fully raised, the tang is withdrawn from its engagement with the slot 13, thus permitting the two frames B and C to be drawn apart and the bag opened.

With this construction, if the bag is not fully closed, that is, the frames B and C are not brought fully into register and the hasp 16 is snapped or pushed down, the extremity of the tang 17 will strike against the inclined margin 14 and this is of such an angle that the tang will wedge the frame B inward and the tang 17 will be guided into the slot 13 without any tendency for the tang to be broken or bent or the keeper to be broken or bent.

Actual use of this device has shown it to be extremely convenient and efficacious for the purpose intended because it is no longer necessary to make certain that the two frames are fully closed one within the other as the snapping or forcing down of the latch will cause the two frames to move into a position of registry, thus distributing the strain on the bag frame. This is particularly desirable where the bag is so well filled that the contents of the bag exert such a pressure as tends to open the bag. It is under these circumstances that there is likelihood of the frames not being entirely closed and of the latches becoming bent in an endeavor to force them to a locked position, and this is obviated by my device.

While I have illustrated and described my improved keeper as being applied to the frames of what are known as Gladstone bags, I wish it distinctly understood that this particular keeper is applicable to frames of other forms of traveling bags, to the frames of satchels and to the frames of hand bags in which keepers of this character are used.

What is claimed is:—

1. In a bag having two coacting frames closing one within the other, the outer frame having a depressible latch provided with a depending tang, a longitudinally slotted keeper attached to the inner frame and extending laterally therefrom, the outer margin of the keeper being inclined laterally and toward the outer face of the frame,

said inclined margin intersecting the slot in the keeper.

2. In a bag having two coacting frames closing one within the other, the outer frame having a compressible latch provided with a depending tang, 5 a longitudinally slotted keeper attached to the inner frame and extending laterally therefrom, the outer margin of the keeper being inclined laterally and toward the outer face of the frame, 10 said inclined margin intersecting the slot in the keeper, the inclined lateral margin of the keeper defining one side of said slot.

3. As an article of manufacture, a keeper for bags of the character described, comprising a strip of rigid metal formed to provide an attaching flange, the body portion of the keeper extending approximately at right angles to the flange and being longitudinally slotted, the outer free margin of the keeper being bent in a direction away from the inside face of the keeper, the inclined margin defining one side of said slot. 5

10 ALLEN T. LONG.
